UNITED STATES PATENT OFFICE.

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY.

SHOE-TRIMMING MACHINE.

Application filed February 26, 1919. Serial No. 279,388.

To all whom it may concern:

Be it known that I, ARTHUR BATES, a subject of the King of Great Britain, residing at Leicester, in the county of Leicester, England, have invented certain new and useful Improvements in Shoe-Trimming Machines; and I do hereby declare the following to be a full, clear, and exact description of the invention, such as will enable others skilled in the art to which it appertains to make and use the same.

This invention relates to shoe trimming machines and more particularly to machines for shaping to proper size and contour such projecting portions of the shoe bottom as help to form the extension in the completed shoe. The illustrative embodiment of the invention shows a construction by which the contour of the part of the flange which is trimmed is determined by the contour of an outsole that has been trimmed or otherwise shaped as to outline prior to its attachment to the shoe.

One method of making welt shoes is disclosed in Letters Patent of the United States to William H. Hooper Nos. 861,178 and 861,180, dated July 23, 1907. By practicing this method the usual rough-rounding operation on the outsole is eliminated because an outsole of final outline is attached instead of a block outsole. The welt then projects laterally beyond the periphery of the outsole the projecting portion thereof constituting one example of what is hereinafter termed a marginal extension, and it becomes necessary to trim such extension to the size and contour of the previously shaped outsole before the edge of the sole and welt can properly be finished.

One object of the present invention is to provide speedy and accurate means for performing a trimming operation on the outward flanges of shoe bottoms, to supplement such operations as those included in the Hooper method of making welt shoes.

A feature of the invention by which this object is accomplished consists in a machine having a flange-trimming knife and a novel gage arranged to bear on the periphery of a previously shaped element other than the flange or extension, such as the outsole, and to control the trimming according to the contour of said shaped element.

To the accomplishment of this object and such others as may hereinafter appear, as

will readily be understood by those skilled in the art, the invention comprises the features and combinations of parts hereinafter described and particularly pointed out in the appended claims.

The preferred form of the invention is illustrated in the accompanying drawings in which:

Figure 1 is a side elevation of the machine with the frame partly removed to disclose the parts inside it. In this view the knife and gage are both in their raised positions preparatory to inserting the work;

Fig. 2 is a detail, in plan, of the knife, its actuating mechanism and the gage, the supporting portion of the frame being shown in section; and

Fig. 3 is a detail, in elevation, of a portion of a welt shoe assembled by the Hooper method with the knife and gage in working position thereon.

In the illustrative embodiment of the invention the machine is shown as a small bench machine. The frame comprises a column 2 provided with a hollow head 4 having an open forward end. The operating tools project from this open end and access to them is gained by lifting a pivoted cover plate 6. The trimming knife 8 is of arcuate form and is clamped in a knife holder 10 formed by an arm projecting forwardly from an oscillatory block 12 carried by horizontal trunnions 14 journaled in the sides of the hollow head 4.

The block 12 is rocked back and forth on its trunnions and consequently the knife 8 is oscillated, it being understood that the center of curvature of the knife is at the axis about where the block 12 rocks. The mechanism for rocking the block 12 is similar in principle to that disclosed in prior Letters Patent of the United States No. 1,139,727, dated May 18, 1915, to Wm. T. B. Roberts, to which reference may be had. Since this knife actuating mechanism is not claimed herein it will suffice to say that the block 12 has a hollow center in which is seated the rectangular head 16 of a stub shaft 18. The head is fast on a vertical pin 20 in the block 12 and the stub shaft is seated in a conical boss 22, in the position indicated by dotted lines in Fig. 1, on the forward end of the driving shaft 24, driven by a belt running over a pulley 26. The action is the same as described in said prior patent last referred

100
105
110

to. Rotation of the boss 22 with the shaft 24 causes the stub shaft 18 to gyrate and, since this stub shaft is not permitted to rotate but executes compound oscillatory motion about the axes of the pin 20 and trunnions 14, the block 12 is simply rocked back and forth thus imparting the desired oscillations to the knife 8. The parts are suitably weighted in order that the oscillations 10 of the knife may be as smooth as possible.

Beneath the knife is a cutting bed 28 of U-shaped form having its legs secured to the frame by screws, as shown in Figs. 1 and 2. This bed is preferably tapering in 15 cross-section to enable it to enter the welt crease and support the portion of the shoe which forms the out-turned flange (see Fig. 3); but the bed 28 is merely a support and cutting block and acts in no way as a 20 gage to determine the path of the cut made by the knife 8.

The path of the trimming cut to be made is determined by a gage 30. The latter is preferably U-shaped so that its legs 32 may 25 be pivoted on the trunnions 14 inside the hollow head 4 (see Fig. 2). One of the legs is provided with a depending arm 34 to which is attached one end of a tension spring 36 the other end of which is secured to a pin 38 extending loosely through 30 the hollow head 4. A wing nut 40 on the threaded pin permits adjustment of the tension of the spring which acts normally to hold the gage 30 down in operative position 35 near the cutting bed 28. In order to raise the gage to an inoperative position to permit insertion and removal of the work a hand lever 42, pivoted on the hollow head 4, is provided with a cam head 44 adapted 40 to engage the arm 34 and force it to the left, as illustrated in Fig. 1.

The gage member also constitutes a novel form of presser-foot by reason of having a roller 46 arranged to bear on the margin of 45 the previously shaped shoe element by which the line of trimming is determined. Preferably the depth of the gage below the bottom of the roller would be less than the thickness of the stock above that to be 50 trimmed, so that the downward stress of the gage would be sustained by the roller and the part on which it rolls instead of by the part being trimmed. This condition avoids a drag on the part being trimmed, enables the 55 latter to pass under the gage without likelihood of catching thereon and minimizes the frictional resistance to the feeding of the work. The level of the gage and presser-foot will therefore be determined not by 60 the part to be trimmed but by the previously shaped part superposed thereon, and since the part to be trimmed will not have any duty to perform it will not militate against uniformly good work by reason of lacking 65 firmness of body or smoothness of surface.

One specific trimming operation is illustrated by Fig. 3. Here a welt shoe assembled after the Hooper method is shown in the machine. The edge of the shaped out-sole bears against the gage 30, the anti-friction roll 46 of which rides on the face of the sole, the whole being held yieldingly to the work by the spring 36. The shoe is fed by the operative and by maintaining contact with the gage the welt is rapidly and accurately trimmed to the contour of the out-sole. 70

Those skilled in the art will recognize that trimming operations other than that illustrated in Fig. 3 can be performed with facility. For example, the machine may be used to trim the middle sole of a McKay shoe to the contour of its shaped outsole as illustrated by dotted lines in Fig. 1. In fact the machine is useful wherever it is desirable 85 to trim the margin of any part of a shoe bottom which projects beyond the last, herein termed a marginal extension, to the contour of another part of the shoe. 80

The nature and scope of the present invention having been indicated and the preferred embodiment of the invention having been specifically described, what is claimed as new is: 90

1. A shoe-trimming machine comprising a cutting bed, a knife arranged to cut against said bed to trim surplus material from a marginal extension projecting beyond the edge of a sole lying on said extension, and a gage arranged to engage the edge of such 100 sole to determine a course of trimming. 95

2. A shoe-trimming machine comprising a cutting bed formed to project into the crease formed by the upper and a marginal extension of a shoe, a knife arranged to cut against said bed to trim surplus material from said marginal extension, and a gage arranged to coact with the edge of a sole 105 lying on said marginal extension to determine a course of trimming. 110

3. A shoe-trimming machine comprising a cutting bed formed and arranged to engage the crease side of a marginal extension projecting from the crease of a shoe, a knife arranged to cut against said bed to trim surplus material from said marginal extension, and a gage arranged to clear 115 said marginal extension and engage the edge of a sole lying thereon and to permit said edge to approach so closely to the knife that said extension will be trimmed substantially to said edge. 120

4. A shoe-trimming machine comprising a cutter for trimming surplus material from a marginal extension projecting from the crease of a shoe, means for sustaining such marginal extension against the stress imposed by the cutter, and a gage formed and arranged to guide the edge of a sole lying on said marginal extension substan- 125 130

tially in tangential relation to the field of trimming so that the marginal extension will be trimmed to the contour of the sole.

5. A shoe trimming machine having, in combination, a shoe support, a gage supported by the face of the outsole and having a bearing on its edge, and a cutter for trimming an out-turned flange which lies above the outsole arranged adjacent to the sole

10 edge engaging position of said gage.

6. A shoe-trimming machine having, in combination, a support for the crease side of the marginal extension of a shoe, a cutter arranged to trim said extension, and a gage arranged to cooperate with the periphery of the outsole so that the latter will clear said cutter.

7. A machine of the character described comprising a work-bed for engaging one face of a marginal extension projecting beyond the periphery of the outsole of a shoe, a knife arranged to cut against said bed to trim said extension, and a gage arranged to bear on said periphery so as to keep the 25 outsole from intersecting the lines of travel of the knife.

8. A shoe-trimming machine comprising cooperative members arranged to clamp superposed layers forming the bottom of a shoe, means arranged to trim surplus material from the margin of one of such layers, and means arranged to engage the periphery of another one of such layers to determine a course of trimming.

35 9. A shoe-trimming machine comprising a cutting bed and a cutter arranged to cooperate therewith to trim surplus material from the marginal extension of a shoe bottom, an edge-gage arranged to engage the periphery of the shoe bottom to determine a course of trimming, and means carried by said edge-gage also to cooperate with said cutting bed to clamp the work.

40 10. A shoe-trimming machine comprising a bed for supporting the marginal extension of a shoe, a cutter arranged to trim a layer of one contour according to the previously defined contour of another layer in confronting relation thereto, and a gage arranged 50 to engage the edge that forms the contour of said other layer so as to determine a course of trimming according to said previously defined contour and so as to preserve the latter.

55 11. A shoe-trimming machine comprising a cutting bed, means arranged to cooperate therewith to clamp superposed layers including an outsole secured to a shoe, a trimming cutter arranged to trim surplus material from one of said layers other than said outsole, and a gage arranged to engage the edge of the outsole to control such trimming so as to preserve the contour of the outsole.

60 12. A shoe-trimming machine comprising

a work-support formed and arranged to engage the crease side of a marginal extension projecting from the crease of a shoe, a gage arranged to engage the edge of an outsole lying on said marginal extension, a roll attached to said gage to ride on the face of the outsole, and a cutter arranged to trim surplus material from said marginal extension so as to preserve the contour of the outsole.

70 13. A shoe-trimming machine comprising cooperative clamping members arranged to clamp the outsole and another shoe element forming a marginal extension projecting from the body of a shoe, means arranged to operate on said other element, and a gage carried by one of said clamping members and arranged to engage the edge of the outsole to keep the latter out of the field of operation of said means.

75 14. A shoe-trimming machine comprising a work-support arranged to support a marginal extension projecting from the body of a shoe, spring-stressed clamping means arranged to engage the face of an outsole lying on said marginal extension so as to exercise its clamping action against said work-support, means arranged to trim surplus material from said marginal extension, and means arranged to retract said clamping 90 means for the introduction and removal of the work.

80 15. A shoe-trimming machine comprising a work-support arranged to support a marginal extension projecting from the body of a shoe, a cutter arranged to trim surplus material from said marginal extension, and spring-stressed means arranged to engage the work so as to function as an edge-gage, a guard for the cutter, and as a clamp to 100 press the work against said work-support.

85 16. A machine of the character described comprising means for supporting the part to be trimmed, a cutter for trimming said part, and a combined work-clamp, work-gage and cutter guard constructed and arranged to clamp the work otherwise than by the part to be trimmed.

90 17. A machine of the character described comprising two work-engaging members arranged to receive between them a marginal extension projecting from the periphery of the outsole of a shoe, and a knife arranged to cut against one of said members to trim said extension, one of said members being formed and arranged to bear against the periphery of the outsole to guide the shoe so that the outsole will clear said knife.

95 18. A machine of the character described comprising a cutting bed arranged to engage the crease side of a marginal extension projecting beyond the periphery of the outsole of a shoe, a knife arranged to cut against said bed to trim said extension, a spring-stressed guard arranged to cover the cutting 100

130

portion of said knife and to tend toward said bed, and an anti-friction roll carried by said guard and arranged to roll on said outsole so as to prevent the guard from bearing on said marginal extension.

19. A machine of the character described comprising a cutting bed arranged to engage the crease side of a marginal extension projecting beyond the periphery of the outsole 10 of a shoe, a knife arranged to cut against said bed to trim said extension, and a spring-stressed device urged normally toward said bed and having one portion arranged to bear on the periphery of the outsole 15 to keep the latter out of the cutting field of said knife, said device having another portion arranged to bear on the tread face of the outsole to prevent the first said portion from clamping said marginal extension.

20. A machine for trimming the marginal 20 extension projecting from the periphery of the outsole of a shoe, comprising a cutting bed and a knife arranged to cut against the same to trim said extension, and a spring-stressed device arranged to cooperate 25 with said bed to clamp the outsole without clamping said marginal extension.

21. A machine of the character described comprising cooperative members arranged to clamp the marginal portion of the outsole 30 of a shoe, a knife arranged to cut against one of said clamping members to trim off any portion of a shoe element projecting laterally beyond the periphery of said outsole, and a gage arranged to guide 35 the outsole so as to keep it clear of said knife.

ARTHUR BATES.
